UNITED STATES PATENT OFFICE.

CHARLES WACHTEL, OF NEW HYDE PARK, NEW YORK.

DESIGN FOR AN ELECTRIC CANDLE LIGHT.

Application filed August 17, 1927. Serial No. 23,124. Term of patent 3½ years.

To all whom it may concern:

Be it known that CHARLES WACHTEL, a citizen of the United States, and resident of New Hyde Park, Long Island, county of Nassau, and State of New York, has invented a new, original, and ornamental Design for an Electric Candle Light, of which the following is a specification, reference being had to the accompanying drawing forming part thereof, in which the figure is a perspective view of an electric candle light embodying my new design.

Referring in detail to the drawing, and particularly to the features that are dominant, the electric candle light embodying the

design comprises an ornamental low cylindrical base A from which upstands a slender stem B having at approximately the mid-height thereof the ornamental sleeve C for the finger grasp, an ornamental candle drip D from which extends the upper portion of the stem terminating in candle-flame shaped electric bulb E, all proportioned as shown in the drawing.

I claim:

The ornamental design for an electric candle light as shown and described.

Dated August 8th, 1927.

CHARLES WACHTEL.
